BAFFLE STRUCTURE IN GASEOUS
DISCHARGE DEVICES

Ward W. Watrous, Jr., Chatham, N. J., assignor
to Chatham Electronics Corporation, Newark,
N. J., a corporation of New Jersey

Application December 29, 1950, Serial No. 203,436

5 Claims. (Cl. 313—193)

1

This invention relates to gaseous discharge devices, generally termed "thyatron," and has particular reference to a form of baffle which is interposed between the cathode and the control electrode.

The use of baffles in gaseous discharge devices is common in the prior art since these structures are useful in preventing "flash-back" or conduction in the reverse direction and also in preventing conduction in the forward direction when the control electrode is regulated for non-conduction. In addition, the baffles are useful for protecting the anode and control electrode from heat radiation from the cathode.

The present invention is directed to a structure which comprises a baffle in the form of a cone. This baffle occupies a certain volume of the space between the control electrode and the cathode and reduces the path of ionized gas molecules, thereby preventing unwanted conduction. It also performs other desirable functions which will be evident from the following description.

One of the objects of this invention is to provide an improved design of gaseous discharge device including a cone baffle arrangement which reduces the volume in the ionized gas region to a minimum.

Another object of the invention is to concentrate the discharge between the anode and cathode on the proper area of the control electrode so that the electrostatic field of the anode can easily initiate ionization and permit the operation of the device with a lower trigger voltage.

Another object of the invention is the protection of the control electrode from the heat energy radiated by the cathode. In this manner the control electrode is reduced in temperature and primary emission is prevented.

Another object of the invention is to deflect particles of emitting material from the cathode, and keep them away from the more active areas of the control electrode.

The invention comprises a gaseous discharge device having an envelope containing gas at a reduced pressure and a cathode which is heated to emit a large supply of electrons. A shielded anode is provided which is connected to a high potential source and attracts electrons when the potential of a control electrode is raised sufficiently positive to initiate the discharge. The control electrode is positioned between the anode and cathode for initiating the flow of electrons to the anode, and a cone-shaped baffle is interposed between the cathode and the control electrode to restrict the movement of ionized particles. The baffle differs from prior art baffles in that it

2

greatly reduces the volume of the grid-cathode chamber in which the ion density is usually high.

For a better understanding of the present invention, together with other and further objects thereof, reference is made to the following description taken in connection with the accompanying drawings.

Fig. 1 is a sectional view taken through the center of the discharge device.

Fig. 2 is a cross-sectional view taken along line 2—2 of Fig. 1.

Referring now to the figures, a cylindrical shield member 10 is positioned axially within an envelope 19, and has attached thereto a control electrode 11 which contains perforations 12 for the passage of electrons when the tube is in its conducting condition. Attached to the shield 10 is an upper disk 13 which acts as a shield for an anode. The anode 14 is supported on a rod 15 which is sealed into the envelope 19 and acts as the anode conductor as well as the anode support. Directly below the control electrode 11 is a baffle 16 supported by two or more brackets 17. The baffle 16 is a disk-shaped member and it is connected directly to the control electrode 11 and the shield 10. A cathode structure 20 is positioned in the lower part of the tube, axially aligned with the shield 10, and comprises a plurality of electron emitting vanes 21. These vanes point inwardly toward the axis of the tube and are supported by a cylindrical member 22. In order to produce large numbers of electrons from the emitting surface, heat is applied to the cathode structure by a number of resistance elements 23 positioned around the cylindrical member 22. These heater elements are connected to a source of electrical power (not shown), and when in operation, assume a temperature of about 1200° centigrade, thereby keeping the cathode vanes 21 at the proper temperature for electron emission.

Surrounding the heating elements 23 are two shield members 24 and 25, having the space between them partly filled with a metallic foil 26, which may be nickel, acting as a heat insulator and preventing the heat from the resistance elements from being dissipated to the shield 10 and the envelope. The shield members 24 and 25 are electrically connected to the cathode emitting vanes 21. This form of cathode has been described in a copending application, Serial No. 203,438, filed December 29, 1950, by W. W. Watrous, Jr.

Directly above the cathode vanes 21 are two heat shielding baffles 30 and 31, each with an axially aligned hole to permit the electrons to escape from the emitting surface. Some dis-

tance above the cathode structure two disk baffles 32 and 33 are mounted in closely spaced parallel relation. These baffles are solely for the prevention of radiant heat being applied directly to the control electrode and the anode. Baffles 32 and 33 are held in place by welded wires 34 and 35.

Above the baffle 33, and generally welded to it by brackets 36, is a cone baffle 37 having a flat portion 38 directly above baffle 33. The inclined portion of the cone baffle extends generally from the outside edge of heat baffle 33 to the baffle 16 mounted adjacent to the control electrode. It will be obvious that this type of baffle can have several forms. For example, the baffle 16 may be attached to the top portion of the cone baffle instead of supporting it from the grid structure, thereby providing an enclosed volume. Also, the lower flat portion of the cone baffle 33 may be formed as a part of the upper heat baffle 33 or the cone baffle may be supported from the grid baffle 16. These variations, however, in no sense detract or alter the operation of the gaseous discharge device.

When such a device is operated, the cathode structure 20 emits a large number of electrons which, with a sufficient electrical field in a rarefied gas produces ionized gas molecules above and surrounding the cathode structure. The anode 14 may be raised to a high positive voltage without conduction between the anode and cathode as long as the control electrode 11 is kept at a suitable potential. This means that there is little or no electric field extending into the grid-cathode region. To initiate conduction in the device the control electrode 11 is usually raised to a small positive voltage. The result is the well known anode-cathode conduction which passes current through the device. The conduction continues as long as the anode voltage is maintained and is not affected by a reduction of the control electrode potential to its former value.

When the anode-cathode electric field is eliminated, the cone baffle rapidly effects deionization and the electric field may again be established without the reoccurrence of conduction. The device is then in condition for another cycle of operations.

While there have been described and illustrated specific embodiments of the invention, it will be obvious that various changes and modifications may be made therein without departing from the field of the invention which should be limited only by the scope of the appended claims.

I claim:

1. A gaseous discharge device comprising, an envelope, a gas within the envelope, a heated cathode for emitting electrons, a shielded anode within said envelope, a control electrode positioned between the anode and cathode for initially controlling the flow of electrons between the anode and cathode, and a cone-shaped baffle positioned between the cathode and the control electrode, said baffle secured mechanically to the cathode and including an inclined surface which directs the flow of electrons toward the periphery of the control electrode.

2. A gaseous discharge device comprising, an envelope, a gas within the envelope, a heated

cathode for emitting electrons, a shielded anode within the envelope, a control electrode positioned between the anode and cathode for initially controlling the flow of electrons between the anode and cathode, and a cone-shaped baffle positioned between the cathode and the control electrode with its larger end adjacent to the control electrode, said baffle secured mechanically to the cathode and including an inclined surface which directs the flow of electrons toward the periphery of the control electrode.

3. A gaseous discharge device comprising, an envelope, a gas within said envelope, a heated cathode enclosed in a cylindrical shield with one end open for the discharge of electrons, a shielded anode within said envelope, a control electrode positioned between the anode and cathode for initially controlling the flow of electrons to the anode, and a cone-shaped baffle positioned between the opening in said cathode shield and the control electrode, said baffle secured mechanically to the cathode shield and including an inclined surface for directing the flow of electrons toward the periphery of the control electrode.

4. A gaseous discharge device comprising, an envelope, a gas within the envelope, a heated cathode for emitting electrons, a shielded anode within the envelope, a control electrode positioned between the anode and cathode for initially controlling the flow of electrons between the anode and cathode, and a baffle shaped in the form of a frustum of a cone positioned between the cathode and the control electrode with its larger end adjacent to the control electrode and its smaller end adjacent to a baffle plate secured to the cathode, said frustum-shaped baffle secured mechanically to the cathode and including an inclined surface which directs the flow of electrons toward the periphery of the control electrode.

5. A gaseous discharge device comprising, an envelope, a gas within the envelope; a shielded cathode, portions of which are heated by the application of electrical energy; a control electrode positioned between the anode and cathode for initially controlling the flow of electrons between the anode and cathode; and a baffle shaped in the form of a frustum of a cone positioned between the cathode and the control electrode for reducing the effective volume between said electrodes with the larger end of the frustum adjacent to the control electrode and the smaller end of the frustum adjacent to a baffle plate secured to the shielded cathode, said frustum-shaped baffle secured mechanically to the cathode and including an inclined surface which directs the flow of electrons toward the periphery of the control electrode.
